CLAIM

The ornamental design for a battery side terminal bushing, as shown and described.

DESCRIPTION

FIG. 1 is a top perspective view of the ornamental design of the battery side terminal bushing, showing said design with shade lines;

FIG. 2 is a bottom perspective view thereof;

FIG. 3 is a front elevation view thereof, the rear elevation view being a mirror image of the front elevation view;

FIG. 4 is a left side elevation view thereof, the right side elevation view being a mirror image of the left side elevation view;

FIG. 5 is a top view thereof;

FIG. 6 is a bottom view thereof;

FIG. 7 is a cross-section view thereof, taken from line 7-7 of FIG. 5; and,

FIG. 8 is a cross-section view thereof, taken from line 8-8 of FIG. 5.

The broken lines shown in the drawings show portions of the battery side terminal bushing which form no part of the claimed design.

The shade lines in the Figures show contour and not surface ornamentation.
